STARCHING MACHINE

Harry D. Forse, Anderson, Ind.

Application May 18, 1938, Serial No. 208,519

18 Claims.

(Cl. 91—24)

This invention relates to a starching machine of universal character.

The chief object of this invention is to provide a starching machine which will, when actuated, automatically feed the article, such as a shirt to be starched, to a starching receptacle and upon withdrawal automatically therefrom to automatically remove the surplus starch and press the starched garment to force the desired amount of starch into the garment and further remove the excess, if there be any, from the garment.

This invention is characterized by the device being continuously operable so long as the motive power is energized.

One feature of the invention consists in the automatic to and fro feeding to the starch containing receptacle of the article to be starched and its automatic removal from said receptacle and its treatment incident to such removal, as previously set forth.

Another feature of the invention includes the provision of a multi-chambered starch receptacle adjustable for the reception of articles to be starched so that the article may be supplied with the proper grade of starch material.

Another feature of the invention is, the safety of the operator is provided for.

The full nature of the invention will be understood from the accompanying drawings and the following description and claims:

In the drawings:

Fig. 1 is a top plan view of the interior mechanism of the starching machine, the cover, conveyor and starch receptacle being omitted for clearness.

Fig. 2 is a side elevational view of the machine, a part of the side casing being removed to show the parts in elevation.

Fig. 3 is a transverse sectional view through the starch receptacle and its support.

Fig. 4 is an enlarged, transverse, sectional view through the movable pressing roll support mechanism.

Fig. 5 is an enlarged, transverse, sectional view through the starch removing and pressing mechanism with the starched garment therebetween and being subject to pressure and excess starch removal.

In the drawings 10 indicates a substantially open-work, rectangular frame structure. 11 indicates a half cover suitably secured to the top portion of the frame and extending but part way thereover from one end toward the midportion. 15 It terminates in a reentrant and arcuately sectioned closure portion 12.

The frame is provided with another cover portion 13 and the same has curved ends 14 and 15. The cover portions 13 and 11 are spaced 60 apart forming a throat 16 which is the garment

receiving throat and through which the garment is applied to the starch in a receptacle therebeneath as hereinafter set forth. A fabric or similar strip 17 overlies the cover 13 and passes under roll 18 carried by the cover 13 in concealed relation and under roll 19 similarly carried and concealed. 5

An actuating arm 20 suitably supports an anchor arrangement 21 within the cover structure 13, and the ends of the portion 17 are suitably secured to the anchorage 21. It will be apparent that as the member 20 moves from the full line position, shown in Fig. 2, toward the left, that the fabric exposed on the top of the cover structure 13 is moved toward the right and upwardly about the end 14 and any garment or article previously starched and positioned thereon, is caused to be moved out of the channel 16 and upwardly from the starch receptacle therebeneath. At the proper time this travel is discontinued. 15 20

The article is removed and another substituted. Thereafter the travel of the conveyor mechanism is reversed and the article is moved into the starch receptacle so that the portions to be starched are immersed in the starch. When the conveyor returns to article receiving position, there is a dwell period in which there is no movement. It is during this interval that the garment is removed from the conveyor and another garment applied to the same. 25 30

The operation is entirely automatic. The movement is to and fro, as it were.

As shown clearly in Fig. 2, there is indicated at 22 an electric motor which through a gear reduction 23 drives a shaft 24. Shaft 24 mounts at one end a sprocket 25. Intermediate its ends it mounts another sprocket which meshes with a chain 26 in turn meshing with a sprocket 27 carried by a shaft 28 rotatably supported in the bracket 29. The shaft 28 has secured to it at 31 the cam 30. This cam 30 engages a cam follower 32 rotatably supported on the shaft 33 extending between the two lever members 34 pivotally mounted as at 35 on the bracket structure 36. 35 40 45

The lower ends of the member 34 are suitably connected together by the pin 37 to which one end of the spring 38 is secured. The opposite end of the spring 38 terminates in an elongated portion 39 threaded as at 40 and the same extends through an opening 41 in the cross member 42 carried by the frame, and a nut 43 bearing on the member 42 adjusts the tension of the spring. 50

Extending across the two members 34 and between the mounting of the cam follower and the spring connection thereto is a pin or shaft 44 which pivotally supports a threaded socket member 45 that is adjustably associated with the threaded end of an actuating rod 46, the lat- 55 60

ter being pivotally mounted as at 47 between the spaced portions 48 carried by the conveyor actuating arm 20, the latter being of dual character as shown in Fig. 1, there being one of said arms 5 20 at each side of the machine and offset as at 20a. The lower ends of these members 20 are pivotally supported as at 49 on the support structures 50, the numeral 49 indicating a shaft extending across the machine as shown in Fig. 1.

10 Suitably secured to an intermediate and upper cross member 51 is a pair of blocks 52 which rotatably support a shaft 53 carrying a roller 54. This roller is of rubber or equivalent character. Immediately therebeneath is positioned a transverse—see Fig. 5—rubber flap of squeegee character and indicated by the numeral 55. It is suitably supported by metal plates 56 secured by screws 57 to the members 52, as shown in said figure. These plates reenforce the flap.

20 The shaft 53—see Figs. 1 and 2—mounts a sprocket 58 with which meshes a sprocket chain 59 in turn meshing with the sprocket 25, previously described. Thus, when the motor 22 is actuated, the roll 54 is rotated and in the clockwise direction, reference being had to Fig. 2.

A pair of channel members 60—see Fig. 4 as well as Fig. 2—is pivotally supported eccentrically of the median plane thereof and at their lower ends, as indicated at 61 and by the support structure 62. A pair of members 63 positioned inside of the two channels 60 is similarly supported at 61. This inside arrangement is shown most clearly in Fig. 4. The two members 63 are suitably connected by a channel construction 64.

30 The two channel members 60 are suitably connected by the transverse member 65 which also is of channel structure.

It has secured intermediate the ends and rigid 40 therewith, a nested threaded embossment 66. The member 64 is apertured as at 67 and the member 65 is apertured as at 68. A pair of bolts 69 have their head portions bearing upon the outer face of the channel 64 and the shank 45 portions extend through the apertures 67 and through apertures 70 in a channel member 71.

The shank also extends through the aperture 68 and concentric with each shank exposed portion is a coil spring 72, one end of which bears 50 against the outer face of the channel member 65 and the other end of which bears against a washer 73, the position of which is adjusted by the nut 74 and locked therein by the nut 75.

55 The two bolts 69 each carry another stop member in the form of a nut 76 between the member 71 and the member 65.

Interposed between the member 71 and the member 64 is a spring 77. A bolt 78 bears against the opposite face of member 71, and in alignment 60 with the spring 77 bearing on the other face thereof, and has threaded connection with the threaded boss 66 and is locked in the adjusted position by the nut 79. Thus, the member 71 is unitized, as it were, with respect to the member 65 and the two channels 60, although it is capable of movement away from the member 65, said movement being resisted by the springs 72 and 77. The two members 63 connected by the transverse channel 64 are unitized, 70 as it were, with respect to the member 71 because of the head portions of the bolts 69 and the stop members, to-wit, nuts 76. The two members 64 and 71, however, are capable of movement to- 75 wards each other in opposition to the spring 77.

Extending oppositely, reference being had to the spring 77, from the cross member 64, is a pair of ears 80 which mount a shaft 81, in turn rotatably supporting a cam follower 82, engaging a cam 83 secured as at 84 to the shaft 28. This 5 construction is shown most clearly in Fig. 4. It is also illustrated somewhat less clearly but in operative relationship to the remaining mechanism as shown in Fig. 2.

Reference will now be had to Figs. 1 and 2. The upper ends of members 60 support the bearing structures 85 which rotatably support the shaft 86 upon which is mounted the roller 87 of rubber or the like and similar to the roller 54. The plates 88 which support the rubber blade 89 are secured by means of screws 90 to the members 85. The blade 89 cooperates with blade 55 to remove surplus starch from the garment as it is being retracted from the starching machine when the rollers are positioned immediately adjacent each other, and with the garment, indicated by the letter A therebetween, as illustrated in Fig. 5. The adjustments are such that preferably roller 87 contacts roller 54. The roller 87 is an idler roller. The roller 54 is a driven roller, and retracts or withdraws the garment from the starch pan by reason of its operative contact with operative idler roller 87.

Reference now will be had to Figs. 1, 2 and 3. In these figures there is illustrated a pair of trackways 91 and a tank 92 is supported by a tray structure, as it were, 93 having the angular, depending portions 94. Rollers 95 are carried by shaft portions 96 supported by the portions 35 94. These rollers 95 roll upon the tracks 91 carried by the frame of the machine. On one support member 94, a short stud 97 is secured and is received by the slot 98 of an arm 99 pivotally supported at 100 in the support member 101.

The shaft 100 extends outwardly from the machine as at 102 and has rigid therewith a lever arm 103 having a handle 104. This handle when actuated, serves to position the carriage structure 93, et cetera, so that any one of the three chambers of the starch tank is positioned beneath the orifice or throat 16. These chambers are formed by partitions 92a—see Fig. 2. As illustrated in Fig. 2, the central chamber is in registration with the throat 16.

A brief description of the operation of the device will now be set forth and from which the simplicity and automatic action of the invention will be readily understood. The garment such as 55 a shirt is first placed by the operator on the conveyor 17. The collar portion and the two cuffs, if they are to be starched, are placed one above the other or side by side, as desired, and the machine being continuously operable then carries 60 the cuffs and collar through the throat 16 through the operation of conveyor 17 which continues its movement sufficiently so the collar and cuffs engage and become immersed in the starch in the tank 92 beneath the throat 16. The operator maintains the remainder of the garment on the conveyor 17 by placing one hand on the garment. The parts are illustrated in Fig. 2 as in the starching position.

Thereafter the idler roll 87 is brought upwardly 70 and to the right from its position shown in Fig. 2, until it engages the garment as shown in Fig. 5. About this time the roller 54 together with conveyor 17, which now reverses its travel, tends to withdraw the collar and cuffs from the starch 75

chamber. The position of lever 28 in Fig. 2 represents the start of the withdrawal operation of conveyor 17.

As the starched elements are withdrawn from the starching tray, the two cooperating rubber blades wipe the surface thereof and the surplus starch is removed from the surface of said portions. As the starched portions are caused to be elevated and removed through the starching machine throat, the pressure exerted by the roller 87 in opposition to the roller 54 is such as to remove all starch in excess of that desired. The movement of the starched article through the pair of cooperating rolls 54 and 87 is facilitated by the clockwise movement of roll 54, roll 87 also revolving in a counterclockwise direction because it is of idler character.

After the garment is released from the rolls, continued travel of the conveyor 17 in the reverse direction fully removes the article from the starching machine throat leaving it on the conveyor from where it is removed from the operator and another article replaced, preliminary to the application of starch thereto. During the initial inward feeding of the article to be starched into the trough 16, the roll 87 is retracted from the pressure applying position, as shown in Fig. 5, to the release position, as shown in Fig. 2. The operation of the device, as stated, is continuous. The device is stopped by stopping the motor in a conventional manner, the details of the control device therefor have intentionally been omitted.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a starching machine, the combination of a starch container, means presenting a garment to be starched to the container and removing same therefrom, pressure applying means, and means operating the pressure means in timed relation to the presenting means operation for pressing the starched garment by the pressure applying means in the withdrawal movement of the garment.

2. A machine of the character defined by claim 1, characterized by the addition of continuously operable power means for operating the presenting means and the pressure applying operating means.

3. A machine of the character defined by claim 1, characterized by the container being of multiple compartment character for different starching mediums and by the addition of means for positioning the selected compartment in operative relation to the presenting means and pressure applying means.

4. A machine of the character defined by claim 1, characterized by the presenting means being of cyclic and oscillatory character for alternately presenting a garment to the container and removing the same therefrom.

5. A machine of the character defined by claim 1, characterized by the pressure applying means including a relatively stationary flexible scraper and a movable flexible scraper, said scrapers having operative pressure scraping action upon the garment therebetween.

6. A machine of the character defined by claim 1, characterized by the pressure applying means including a pair of rotatable rollers which are relatively movable, one of which has a fixed position, said rollers having operative pressure squeezing action upon the garment therebetween, said pressure applying means further including a relatively stationary flexible scraper and a movable flexible scraper, said scrapers having operative pressure scraping action upon the garment therebetween, and interposed between said rollers and said container, and means connecting the movable scraper and movably positioned roller together for simultaneous and similar movement. 5

7. A machine of the character defined by claim 1, characterized by the pressure applying means including a pair of rotatable rollers which are relatively movable, one of which has a fixed position, said rollers having operative pressure squeezing action upon the garment therebetween, and means for rotating the fixed position roller, said pressure applying means further including a relatively stationary flexible scraper and a movable flexible scraper, said scrapers having operative pressure scraping action upon the garment therebetween, and interposed between said rollers and said container, and means connecting the movable scraper and movably positioned roller together for simultaneous and similar movement. 10

8. A machine of the character defined by claim 1, characterized by the pressure applying means including a pair of rotatable rollers which are relatively movable, one of which has a fixed position, said rollers having operative pressure squeezing action upon the garment therebetween, and means for rotating the fixed position roller and in a direction to facilitate garment removal from the container, said pressure applying means further including a relatively stationary flexible scraper and a movable flexible scraper, said scrapers having operative pressure scraping action upon the garment therebetween, and interposed between said rollers and said container, and means connecting the movable scraper and movably positioned roller together for simultaneous and similar movement. 15

including a yielding arrangement, an actuated member, means connecting same to the support and constraining the actuated member toward the support but permitting relative movement therebetween, other means constraining the actuated member away from the support in opposition to the first mentioned means, and means limiting the approach movement between the support and actuated member.

10 12. In a starching machine, a garment engaging pressure applying member, a tiltable support therefor, and means tilting the support for tilting the member into pressing position, said means including a yielding arrangement, an actuated member, means connecting same to the support and constraining the actuated member toward the support but permitting relative movement therebetween, other means constraining the actuated member away from the support in opposition to the first-mentioned means, means limiting the separating movement between the support and actuated member, and means limiting the approach movement between the support and actuated member.

20 13. In a starching machine having a garment engaging pressure applying member, the combination of a main support for said member and tiltably mounted and means for tilting said support including a power operable member remote 30 from the pivotal axis, a floating member operatively interposed between the power operable member and the support, means connecting the power operable member to the support and constraining the former toward the latter but permitting relative movement therebetween, means interposed between the power operable member and the floating member and constraining same toward separated relation, and means limiting movement of the floating member toward the 40 support, the initial constraint having a direction opposite the direction of pressure application.

14. In a starching machine having a garment engaging pressure applying member, the combination of a main support for said member and 45 tiltably mounted and means for tilting said support including a power operable member remote from the pivotal axis, a floating member operatively interposed between the power operable member and the support, means connecting the 50 power operable member to the support and constraining the former toward the latter but permitting relative movement therebetween, means interposed between the power operable member and the floating member and constraining same 55 toward separated relation, and means limiting movement of the floating member toward the support, the initial constraint having a direction opposite the direction of pressure application, the last mentioned means being of adjustable character and cooperating with the separating constraint means.

60 15. In a starching machine having a garment engaging pressure applying member, the combination of a main support for said member and tiltably mounted and means for tilting said support including a power operable member remote from the pivotal axis, a floating member operatively interposed between the power operable member and the support, means connecting the 65 power operable member to the support and constraining the former toward the latter but permitting relative movement therebetween, means interposed between the power operable member and the floating member and constraining same 70 toward separated relation, and means limiting

movement of the floating member toward the support, the initial constraint having a direction opposite the direction of pressure application, the first mentioned constraint means having cooperative association with the floating member 5 in the form of a stop arrangement.

16. In a starching machine having a garment engaging pressure applying member, the combination of a main support for said member and tiltably mounted and means for tilting said support including a power operable member remote from the pivotal axis, a floating member operatively interposed between the power operable member and the support, means connecting the power operable member to the support and constraining the former toward the latter but permitting relative movement therebetween, means interposed between the power operable member and the floating member and constraining same toward separated relation, and means limiting movement of the floating member toward the support, the initial constraint having a direction opposite the direction of pressure application, the last mentioned means being of adjustable character and cooperating with the separating constraint 25 means, the first mentioned constraint means having cooperative association with the floating member in the form of a stop arrangement.

20 17. In a starching machine having a garment engaging pressure applying member, the combination of a main support for said member and tiltably mounted and means for tilting said support including a power operable member remote from the pivotal axis, a floating member operatively interposed between the power operable member and the support, means connecting the power operable member to the support and constraining the former toward the latter but permitting relative movement therebetween, means interposed between the power operable member and the floating member and constraining same toward separated relation, means limiting movement of the floating member toward the support, the initial constraint having a direction opposite the direction of pressure application, and another pivotal support for pivotally supporting the power operable member upon an axis substantially coincident with tilting axis of the main support.

30 18. In a starching machine having a garment engaging pressure applying member, the combination of a main support for said member and tiltably mounted and means for tilting said support including a power operable member remote from the pivotal axis, a floating member operatively interposed between the power operable member and the support, means connecting the power operable member to the support and constraining the former toward the latter but permitting relative movement therebetween, means interposed between the power operable member and the floating member and constraining same toward separated relation, means limiting movement of the floating member toward the support, the initial constraint having a direction opposite the direction of pressure application, and another pivotal support for pivotally supporting the power operable member upon an axis substantially coincident with tilting axis of the main support, the first mentioned constraint means having cooperative association with the floating member in the form of a stop arrangement.
